UNITED STATES PATENT OFFICE.

GIOVANNI EMANUELE ELIA, OF WESTMINSTER, ENGLAND, ASSIGNOR TO VICKERS LIMITED, OF WESTMINSTER, LONDON, ENGLAND, A BRITISH COMPANY.

SUBMARINE MINE.

Application filed February 2, 1924. Serial No. 690,217.

To all whom it may concern:

Be it known that I, GIOVANNI EMANUELE ELIA, a subject of the King of Italy, residing at Vickers House, Broadway, Westminster, in the county of London, England, have invented certain new and useful Improvements in or Relating to Submarine Mines, of which the following is a specification.

10 This invention relates to submarine mines of the kind in which the separation of the flotation chamber from the anchor is adapted to take place at or near the sea bed or to mines of other types which are to be anchored in comparatively deep water.

When a submarine mine is to be anchored in deep water, the flotation chamber, after it is launched and before it separates from the anchor, may be subjected to such a high degree of pressure as will rupture or crush the buoyancy compartment of the flotation chamber, as, in order to reduce the weight of the flotation chamber it is usually constructed from comparatively thin metal which, in 25 the case of a standard construction of mine, is only capable of withstanding the hydrostatic pressure prevailing at depths of less than about 300 feet, and it is the object of the present invention to enable mines of 30 this kind to be anchored safely in deep water, without increasing the thickness of the metal and consequently the dimensions of the flotation chamber.

In the case of mines provided with a 35 plummet for depth regulating purposes, the flotation chamber, the anchor and the plummet have been connected together so as to constitute a single launching unit and means such as a hydrostat have been provided for 40 releasing the parts of the mine from one another at a short distance below the surface, the flotation chamber ascending to the surface and the parts of the mine thereafter positioning in the usual manner.

45 According to the present invention means are provided for releasing the flotation chamber from the anchor, when the complete mine, after launching, and during its descent to the sea bed, reaches a depth above that at which rupture of the flotation chamber is liable to take place, the mooring cable being permitted to pay out and the anchor to separate from the flotation chamber, the

latter remaining substantially stationary at approximately the said depth, until the anchor reaches the sea bed. The flotation chamber is thereby kept above the depth for which the resistance of the flotation chamber has been calculated, while the anchor descends alone to the sea bed, the subsequent 55 operations of anchoring the flotation chamber at the desired depth beneath the surface being carried out in any convenient manner. To this end hydrostatically controlled means may be provided which, on the flotation chamber reaching the depth for which the hydrostat has been set, and above that at which the flotation chamber is liable to be damaged, are adapted to release the flotation chamber from the sinker and allow 60 the mooring cable to pay out at a speed corresponding to that at which the anchor descends to the sea bed whilst the flotation chamber remains substantially stationary, 65 that is, the braking means maintain a tension in the mooring cable equal to or slightly less than the buoyancy of the flotation chamber.

A time releasing device, as hereinafter described, may also be fitted to provide for 70 cases where the mine is launched in water of a less depth than the safe limit for the flotation chamber.

75 After the anchor reaches the sea bed the brake resistance may be reduced to such an extent as to enable the flotation chamber to ascend at a suitable speed by the lifting effect of its buoyancy, the paying out of the mooring cable being finally stopped and the mooring cable drum locked in any suitable 80 known manner, for example by the method described in English Patent No. 163,339, or as described in the company's copending United States application Serial No. 690,856.

85 In order that the said invention may be 90 clearly understood and readily carried into effect the same will now be described more fully with reference to the accompanying drawing, in which:—

95 Figure 1 is a sectional end elevation of 100 the sinker and part of the flotation chamber of a submarine mine constructed according to one form of the present invention.

105 Figure 2 is a sectional elevation of the sinker shown at Figure 1 and

Figure 3 is a sectional elevation of another form of sinker.

Figure 4 is a detail view of a suitable form of hydrostat for releasing the flotation chamber from the sinker, and

Figures 5 and 6 are a sectional elevation and an end view respectively of a compound time and hydrostatic release for the flotation chamber and anchor.

A (Figure 1) is the flotation chamber and B is the sinker. The mine A is held rigidly on the sinker B until after launching by means of a hydrostatic release P which operates at a safe depth of immersion of the flotation chamber. A suitable form of hydrostatic device for allowing the mine to separate from the sinker when the combination has descended to a safe depth of immersion for the flotation chamber, is shown in elevation at Figure 1 and in section at Figure 4, the device comprising a hydrostat P and two links R, R¹ which respectively connect the parts of the hydrostat to the flotation chamber A and to the sinker B. The diaphragm p of the hydrostat is open, through passages p¹, to the hydrostatic pressure and it is connected to a spindle p² surrounded by a spring p³ and the spindle is provided at its upper end with a plunger which is slidably mounted within a central recess r in the link R. Positioned within lateral slots in the link R and projecting into recesses in the casing of the hydrostat are the balls s, s of a ball releasing device, the balls, in the position of the parts shown at Figure 4, rigidly holding together the hydrostat P and the link R.

When a safe depth of submersion for the mine has been reached, the water pressure, acting on the diaphragm p overcomes the spring p³ and draws down the spindle p² and the plunger at its upper end until the balls s are free to move into the recess r and thus to release the casing of the hydrostat from the link R, whereupon the flotation chamber A is free to separate from the anchor B. The mine, however, may be released by both a hydrostatic release and also by a time release, which latter may be operated by a dashpot or a soluble plug. A suitable arrangement of a compound release, where the time release is constituted by a dashpot device, is shown at Figures 5 and 6, and comprises a depending bolt M which is connected to the mine casing and on which a rocking lever m is pivotally mounted. The ends of the rocking lever m are recessed as shown and, supported on knife edges formed within openings in a pair of tubular members O, O¹ are a hydrostatic releasing device K and a time releasing device N, these devices being secured to the members O and O¹ by ball releasing devices. The devices K and N are provided with lugs o, o¹ at their lower ends and on the mine casing is a pro-

jection Q to which the releasing devices are secured by bolts R².

The operation of the hydrostatic release K is similar to that of the hydrostat P already described above, but in lieu of releasing the link R the balls s, s are adapted to release the member O. The time releasing device comprises a cylinder divided into two parts n, n¹ by a partition n² which latter is

provided with a central opening n³ controlled by a non-return valve n⁴. The opening n³, as also an opening n⁵, place the upper and lower parts of the cylinder in communication with one another when the ball valve is open.

In the upper chamber n is a piston n⁶ normally maintained at the top of the cylinder by a spring n⁷ the chamber n being filled with a fluid such as oil. Connected to the piston n⁶ is a rod n⁸ which normally locks the member O to the casing by

means of the balls n⁹. The top of the chamber n above the piston n⁶ is in communication with the surrounding water by openings n¹⁰ and, in view of this arrangement, and on the mine being launched, the hydrostatic

pressure of the water will overcome the resistance of the spring n⁷ and gradually press the piston n⁶ towards the bottom of the cylinder, the ball valve n⁴ being forced off its seat and the fluid being gradually transferred through the openings n³ and n⁵ into

the lower chamber n¹. The arrangement of the parts is such that the time taken to force the oil from the upper part n of the cylinder through the ball valve n⁴ into the lower part n¹ of the cylinder is equivalent to the time taken to totally pay out the maximum length of mooring cable carried on the mooring cable drum so that the release of the flotation chamber by means of the time re-

lease N cannot take place before actuation of the hydrostatic release K. In view of this arrangement it will be clear that on either of the devices K or N being operated

one or other of the ball releasing devices will release either the member O or the member O¹. On such release taking place the hydrostat K or the time release N will fall away from either the member O or O¹

and, owing to the pull exerted by the other devices on the opposite end of the rocking lever m, the latter will oscillate about its fulcrum and allow the other device to fall away from the knife edges on which it is supported. Consequently both devices will fall substantially simultaneously clear of the flotation chamber A thus allowing it to separate from the anchor B.

The flotation chamber may also be released independently of any such special releasing means, but by using a compound time and hydrostatic release as aforesaid, the hydrostatic release, should the mine be launched in water of greater depth than

the safe limit of depth for the flotation

chamber, will operate to release the flotation chamber from the sinker and prevent it from descending below the said depth, while, in cases where the mine is launched 5 in water of a less depth than this safe limit, the time release is automatically brought into operation, after a predetermined interval of time.

After the mine is released from the anchor 10 the mooring rope B^1 is paid out from the mooring rope drum C under the control of the gear pump brake D driven from the drum C by a wheel E and pinion F . The resistance of the brake caused by the 15 resistance of the flow of oil from the delivery to the suction side through the passage d is adjusted by a screw down valve d^1 so that the braking resistance on the mooring rope corresponding to the speed 20 of descent of the anchor is approximately equal to or slightly less than the buoyancy of the mine; consequently the mine remains approximately at, or rises very slowly above, the depth of safe immersion of the flotation 25 chamber. A second connection between the delivery and suction of the pump brake is provided by means of a pipe d^2 which, during the descent of the anchor is totally blocked by a plunger d^4 until after the 30 sinker has reached the sea bed. Hydrostatic pressure entering through holes e acts on the underside of a piston d^5 and pushes up the piston and the plunger d^4 to which it is connected, thereby forcing the fluid, such 35 as oil, which is in the chamber g through the small hole h and past the spring loaded ball valve j into the air chamber k . The size of the hole is such that the hydrostatic pressure can push the piston right up in a 40 period of time somewhat longer than the time taken for the sinker to reach the sea bed when launched in a depth of water corresponding to the paying out of the maximum length of mooring rope carried on the 45 mooring rope drum. When the plunger f has been pushed to the top of its cylinder, an annular passage d^6 formed by a reduced portion of the plunger d^4 opens the passage through the pipe connection d^3 and so reduces 50 the brake resistance of the pump that the mine can rise at the usual speed until it reaches the set depth of immersion, whereupon the mooring rope drum is locked by any known means such as that described 55 in Patent No. 163,339 or as described in co-pending application No. 30,568 of 1922.

An alternative arrangement of brakes is shown at Figure 3. In this instance two separate oil pump brakes G and H are 60 fitted. Whilst the anchor is descending the mooring rope drum C drives both brakes by means of toothed wheels E , E^1 which engage with the pinion F , F^1 of the brakes H and G . The total resistance of the two 65 brakes together is equal to that necessary

to keep the mine at approximately constant depth. After the sinker reaches the sea bed the time dashpot release J of similar construction to that previously described completely withdraws the plunger M^2 from 70 engagement with the toothed wheel E^1 which is loosely mounted on the mooring rope drum. The brake G is thus entirely disengaged and the mooring rope is paid out subject only to the resistance of the brake H 75 which is such as to allow the mine to ascend at a suitable speed.

In lieu of either of the aforesaid arrangements any other type of frictional or fluid resistance brake may be used and the releasing plunger M may, if desired, be operated under the control of a soluble plug, by a simple hydrostat, or by other means suitable to effect release of the second brake after the sinker reaches the sea bed. 85

What I claim and desire to secure by Letters Patent of the United States is:—

1. A submarine mine comprising a flotation chamber, a sinker, a mooring rope connecting said flotation chamber to said sinker, 90 means for releasing the flotation chamber from the sinker when the mine reaches a depth above that at which rupture of the flotation chamber is liable to take place, and means for allowing the mooring cable to unwind at a speed corresponding substantially to that at which the sinker descends to the sea bed, whereby the flotation chamber remains substantially stationary at the said depth until the sinker reaches the sea bed. 95

2. A submarine mine comprising a flotation chamber, a sinker, a mooring rope connecting said flotation chamber to said sinker, means for releasing the flotation chamber from the sinker when the mine reaches a 100 depth above that at which rupture of the flotation chamber is liable to take place, and braking means which maintain a tension in the mooring cable equal to or slightly less than the buoyancy of the flotation chamber 105 whereby the mooring cable is allowed to unwind at a speed corresponding substantially to that at which the anchor descends to the sea bed so that the flotation chamber remains substantially stationary at the said 110 depth until the sinker reaches the sea bed.

3. A submarine mine comprising a flotation chamber, a sinker, a mooring rope connecting said flotation chamber to said sinker, means for releasing the flotation chamber 115 from the sinker when the mine reaches a depth above that at which rupture of the flotation chamber is liable to take place, braking means which apply such a brake resistance that the mooring cable is allowed 120 to unwind at a speed corresponding substantially to that at which the sinker descends to the sea bed, and means by which the brake resistance, on the sinker reaching the sea bed, is reduced to such an extent as to en- 125

able the flotation chamber to ascend at a suitable speed by the lifting effect of its buoyancy.

4. A submarine mine comprising a flotation chamber, a sinker, a mooring rope connecting said flotation chamber to said sinker, means for releasing the flotation chamber from the sinker when the mine reaches a depth above that at which rupture of the flotation chamber is liable to take place, braking means which apply such a brake resistance that the mooring cable is allowed to unwind at a speed corresponding substantially to that at which the sinker descends to the sea bed, means by which the brake resistance, on the sinker reaching the sea bed, is reduced to such an extent as to enable the flotation chamber to ascend at a suitable speed by the lifting effect of its buoyancy and means for stopping the unwinding of

the mooring cable when the flotation chamber has reached the depth at which it is to be finally anchored.

5. A submarine mine comprising a flotation chamber, a sinker, a drum within said sinker, a mooring rope connecting said flotation chamber to said sinker, hydrostatically controlled means for releasing the flotation chamber from the sinker on the mine reaching a depth above that at which the flotation chamber is liable to be damaged, and time operated means for releasing the flotation chamber from the sinker at a predetermined interval after launching in cases where the mine is launched in water of a less depth than the safe limit for which the hydrostatically controlled means have been set.

GIOVANNI EMANUELE ELIA.
